UNITED STATES PATENT OFFICE.

ALBERT HUNT, OF LONDON, ENGLAND.

DESIGN FOR A BOARD FOR PLAYING A GAME.

48,470.

Specification for Design.

Patented Jan. 18, 1916.

Application filed October 14, 1915. Serial No. 55,906. Term of patent 3½ years.

To all whom it may concern:

Be it known that I, ALBERT HUNT, subject of the King of Great Britain and Ireland, residing at 2D, Oxford and Cambridge Mansions, London, in the county of London, England, have invented a new, original, and ornamental Design for a Board for Playing a Game, of which the following is a specification, reference being had to the accompanying drawing, forming part thereof.

The figure is a plan view of a board for playing a game, showing my new design.

I claim:

The ornamental design for a board for playing a game, as shown.

ALBERT HUNT.

Witnesses:

GEORGE FREDRIC RAYNER,
FRANK WILLIAM PATTISON.
